UNITED STATES PATENT OFFICE

ELMER BABB, OF NEW YORK, AND ANTHONY W. ZABOROWSKI, OF JAMAICA, NEW YORK

DESIGN FOR AN INK OR OTHER FLUID CONTAINER

Application filed September 21, 1932. Serial No. 45,014. Term of patent 14 years.

To all whom it may concern:

Be it known that we, ELMER BABB and ANTHONY W. ZABOROWSKI, citizens of the United States, residing, respectively, at New York city, in the county of Bronx and State of New York, and at Jamaica, Long Island, in the county of Queens, city and State of New York, have invented a new, original, and ornamental Design for an Ink or Other Fluid Container, of which the following is a specification, reference being had to the accompanying drawing, forming part thereof.

In the said drawing:

Fig. 1 is a perspective view of the container, showing our new design;

Fig. 2 is a top plan view of the container; and

Fig. 3 is a side view thereof.

We claim:

The ornamental design for an ink or other fluid container, substantially as shown.

ELMER BABB.
ANTHONY W. ZABOROWSKI.
